Pittsburgh, Pa., a corporation of
Delaware

No Drawing. Original No. 1,836,919, dated December 15, 1931, Serial No. 457,500, May 29, 1930. Application for reissue March 13, 1934, Serial No. 715,378

15 Claims. (Cl. 23—213)

This invention relates to a process for the production of hydrogen, low in or free from carbon monoxide, and for eliminating carbon monoxide from water gas or from gaseous mixtures of similar composition.

5 The decomposition of water by means of incandescent carbon (preparation of water gas) proceeds in accordance with the equation.

10 At lower temperatures, below 1,000° C., CO_2 is formed, in addition to CO , in accordance with the equation

15 A state of equilibrium, dependent on the temperature, is established between CO and CO_2 , which is displaced, in favor of the CO , at high temperature. Since theoretically, the formation 20 of hydrogen according to Equation II leads to a gaseous mixture free from carbon monoxide and, in addition requires a far smaller expenditure of heat, it would be of advantage to conduct the hydrogen process in accordance with that equation. The gaseous mixture obtained at lower 25 temperature would also be the most suitable for the technical recovery of hydrogen, since the precipitation of carbon dioxide is far simpler, in practice than the elimination of carbon monoxide. The difficulty, however, arises that the reaction velocity, which becomes progressively 30 smaller as the temperature falls, is far too slow for practical working at those temperatures at which the equilibrium is established in favor of Equation II.

35 Formerly, attempts were frequently made to overcome this inconvenience, especially in order to make possible the direct recovery of hydrogen, almost free from carbon monoxide, by conducting the process in accordance with Equation II. In order to increase the velocity of the reaction, it has been proposed, inter alia, to employ hydrates or carbonates of the alkalis, or the corresponding water-soluble compounds, of the alkaline earths 40 as catalysts. According to this known process, materials containing carbon, impregnated with the said water-soluble compounds, were to be exposed, in an incandescent state, to the action of ordinary or superheated steam.

45 The proposal advanced in this direction, however, did not prove successful, and consequently, for the technical recovery of hydrogen from water gas, the water gas process was allowed to proceed at high temperature, the carbon monoxide 50

being then removed from the resulting gaseous mixture in a separate working operation.

This result was secured, in addition to liquefaction, chiefly by oxidizing the carbon monoxide to carbon dioxide by the aid of steam and with the agency of catalysts. This process is economical, if the oxidation of the carbon monoxide be carried out under high pressure, but, in its really valuable methods of procedure, it is by no means simple, and at the same time, furnishes a 10 mixture of hydrogen and carbon dioxide, which still always contains carbon monoxide, even though in small amounts, so that a chemical purification (such as washing the gas with solutions of cuprous salts) is still necessary in order to obtain pure hydrogen. 15

Another process for the recovery of pure hydrogen from water gas containing carbon monoxide, has recourse, in the oxidation of the carbon monoxide by means of steam, to fixing the carbon dioxide by substances capable of absorbing same, lime in particular, for accelerating the reaction. By the continuous removal of the carbon dioxide from the reaction mixture, the equilibrium associated with the reaction $CO + H_2O = H_2 + CO_2$ is 25 displaced in favor of the carbon dioxide. In carrying out this process, the water gas is passed, together with an excess of steam, over lime which is heated, in a retort, to a temperature below the decomposition temperature of calcium carbonate. 30 An addition of catalytic substances has been found to facilitate the reaction. As carbon dioxide-absorbing substance lump lime is preferably employed, which is rapidly transformed into calcium carbonate, even in the interior, during the passage of the water gas. From this carbonate, quick lime is recovered by calcining, and is again brought into reaction with water gas. Further proposals have been made, in order to improve this process, the employment of steam 35 in exactly, or approximately, stoichiometric proportions being particularly recommended.

The present invention solves, in the first place, the problem of the direct production of a mixture of hydrogen and carbon dioxide, low in, or free 45 from, carbon monoxide, by the action of steam on carbon (or substances containing carbon), in the presence of additions which accelerate the reaction, and under conditions substantially approximating Equation II of the water gas process. 50 According to the invention, the process is conducted with the employment of magnesia, magnesium carbonate or magnesium hydroxide, as catalysts, at a temperature which, though, above the decomposition temperature of magnesium 55

carbonate, does not substantially exceed 750° C. The invention is based upon the fact that the equilibria associated with the reaction

are of decisive importance for the production of hydrogen free from carbon monoxide. From this point of view, the temperature of 500° C. is the most favorable temperature for the reaction, in 10 that at this temperature, the equilibrium is practically completely displaced, in favor of carbon dioxide. Above 500° C., CO_2 in the presence of C is reconverted into CO to an increasing extent as the temperature rises, so that, for the formation 15 of a gaseous mixture low in carbon monoxide, the range of temperature above 750° C., is not longer to be considered. Below 700-750° C., however, the reaction velocity of the hydrogen process is already retarded to such an extent that the 20 reaction cannot be carried out on a technical scale. The problem therefore arose of finding an effective and insensitive contact mass which will enable the reaction velocity of the formation 25 of hydrogen to be sufficiently increased in the range of temperature below 750° C. A mixture of carbon with magnesium carbonate has been found admirably suited for the purpose. This is based on the relatively low decomposition temperature of magnesium carbonate, which can be 30 reduced to even below 500° C. by diluting the gas phase with steam, and thereby lowering the partial pressure of the carbon dioxide.

At 500° C. the reaction

occurs to form an equilibrium, when the amounts of steam employed correspond to the stoichiometrical proportions of Equation II, or only slightly exceed those proportions. Magnesium 40 carbonate therefore has the capacity of rapidly absorbing, and again parting with, carbon dioxide in the hydrogen process conducted in accordance with Equation II, at the optimum temperature suitable for reliably preventing the formation 45 of carbon monoxide. This is not the case, either with the alkali carbonates or calcium carbonate. According to the invention, the performance of the hydrogen process with the use of magnesium carbonate as catalyst, at temperatures 50 which do not substantially exceed 500° C., enables hydrogen, practically free from carbon monoxide, to be obtained directly.

If, for example, wood charcoal be mixed with magnesium carbonate, in the proportions of 100 parts by weight of charcoal to 5-25 parts by weight of magnesium carbonate, and such mixture be treated, at about 500° C., with the stoichiometrical amount of steam (corresponding to 2 molecules of H_2O to 1 mol. of C), the reaction 60 proceeds in practical accordance with Equation II and with quite sufficient velocity. The process is also of importance for the production of mixtures of hydrogen and carbon dioxide. However, since, as is known, the carbon dioxide can 65 be easily separated from this mixture, the process primarily affords a practically applicable method for the recovery of pure hydrogen.

Of course, magnesium oxide or hydroxide, which are immediately converted into magnesium carbonate, can be introduced into the reaction in place of magnesium carbonate. The process can also be carried out with crude materials which contain magnesium oxide or hydroxide in sufficient amount. The catalyst remains unaltered, 75 in composition and active, without regeneration,

so that only the gasified carbon has to be replaced. Since the course of the reaction for the formation of hydrogen in accordance with Equation II is slightly endothermic, the reaction temperature of approximately 500° C. can be maintained by the application of a very small amount of heat. ⁵

Claims for gasifying charcoal with steam, in the specified manner, for the direct production of a mixture of hydrogen and carbon dioxide, free from carbon monoxide, are contained in Patent No. 1,926,587, issued September 12, 1933, on an application constituting a division of my original application Serial Number 457,500. The invention is, however, especially useful in eliminating, ¹⁰ or substantially eliminating, carbon monoxide from water gas, or other gaseous mixtures of similar composition, containing same, and in this aspect of the invention the gas, or gaseous mixture, containing carbon monoxide, is passed, in ¹⁵ association with steam, over a mixture of charcoal (or substances containing carbon) and magnesium oxide or hydroxide or carbonate, which is maintained at a temperature above the decomposition temperature of magnesium carbonate, ²⁰ but not substantially exceeding 500° C. The course of the reaction may be expressed by the following equations:

30

Since the reaction $2\text{CO} = \text{C} + \text{CO}_2$ is decidedly exothermic, only a very small supply of heat from outside is required also in this case, in order to maintain the temperature at about 500° C. If, in this method of carrying out the process, the amount of steam added be only just sufficient for the carbon formed in accordance with the equation $2\text{CO} = \text{C} + \text{CO}_2$ to combine, in the nascent state, with the steam, in accordance with the Equation II of the hydrogen process, and form carbon dioxide, the catalytic material will remain entirely unaltered. The process can be carried out quietly, without any further addition of carbon being needed. In any event, however, no reactivation of the catalyst material is required, because, even in this case, the working temperature is higher than the decomposition temperature of the magnesium carbonate. ⁵⁰

It is sufficient to bring the gases, prior to their passing out of the apparatus, into contact, for 20-30 seconds, with a layer of contact material which is maintained at a temperature not substantially exceeding 500° C. With this proviso, ⁵⁵ zones of the contact material which are traversed by the gases in an earlier stage, can also be heated to temperatures between 500 and 750° C., for the purpose of accelerating the reaction. ⁶⁰

Example 1

An intimate mixture of wood charcoal and calcined magnesite, and containing, for example, 1 part by weight of magnesium oxide for every 4 parts by weight of charcoal, is allowed to descend through an externally heated shaft furnace in which the contact mass is maintained at about 500° C. Steam is passed, in counter flow, through the descending charge. The contact mass, low in charcoal, issuing at the lower end of the shaft is again mixed with sufficient added charcoal to restore the desired magnesium oxide-charcoal ratio, above noted, and the resulting mixture is returned into the top of the shaft furnace, thus permitting a cyclic opera- ⁶⁵ ⁷⁰ ⁷⁵ ⁸⁰ ⁸⁵ ⁹⁰ ⁹⁵ ¹⁰⁰ ¹⁰⁵ ¹¹⁰ ¹¹⁵ ¹²⁰ ¹²⁵ ¹³⁰ ¹³⁵ ¹⁴⁰ ¹⁴⁵ ¹⁵⁰ ¹⁵⁵ ¹⁶⁰ ¹⁶⁵ ¹⁷⁰ ¹⁷⁵ ¹⁸⁰ ¹⁸⁵ ¹⁹⁰ ¹⁹⁵ ²⁰⁰ ²⁰⁵ ²¹⁰ ²¹⁵ ²²⁰ ²²⁵ ²³⁰ ²³⁵ ²⁴⁰ ²⁴⁵ ²⁵⁰ ²⁵⁵ ²⁶⁰ ²⁶⁵ ²⁷⁰ ²⁷⁵ ²⁸⁰ ²⁸⁵ ²⁹⁰ ²⁹⁵ ³⁰⁰ ³⁰⁵ ³¹⁰ ³¹⁵ ³²⁰ ³²⁵ ³³⁰ ³³⁵ ³⁴⁰ ³⁴⁵ ³⁵⁰ ³⁵⁵ ³⁶⁰ ³⁶⁵ ³⁷⁰ ³⁷⁵ ³⁸⁰ ³⁸⁵ ³⁹⁰ ³⁹⁵ ⁴⁰⁰ ⁴⁰⁵ ⁴¹⁰ ⁴¹⁵ ⁴²⁰ ⁴²⁵ ⁴³⁰ ⁴³⁵ ⁴⁴⁰ ⁴⁴⁵ ⁴⁵⁰ ⁴⁵⁵ ⁴⁶⁰ ⁴⁶⁵ ⁴⁷⁰ ⁴⁷⁵ ⁴⁸⁰ ⁴⁸⁵ ⁴⁹⁰ ⁴⁹⁵ ⁵⁰⁰ ⁵⁰⁵ ⁵¹⁰ ⁵¹⁵ ⁵²⁰ ⁵²⁵ ⁵³⁰ ⁵³⁵ ⁵⁴⁰ ⁵⁴⁵ ⁵⁵⁰ ⁵⁵⁵ ⁵⁶⁰ ⁵⁶⁵ ⁵⁷⁰ ⁵⁷⁵ ⁵⁸⁰ ⁵⁸⁵ ⁵⁹⁰ ⁵⁹⁵ ⁶⁰⁰ ⁶⁰⁵ ⁶¹⁰ ⁶¹⁵ ⁶²⁰ ⁶²⁵ ⁶³⁰ ⁶³⁵ ⁶⁴⁰ ⁶⁴⁵ ⁶⁵⁰ ⁶⁵⁵ ⁶⁶⁰ ⁶⁶⁵ ⁶⁷⁰ ⁶⁷⁵ ⁶⁸⁰ ⁶⁸⁵ ⁶⁹⁰ ⁶⁹⁵ ⁷⁰⁰ ⁷⁰⁵ ⁷¹⁰ ⁷¹⁵ ⁷²⁰ ⁷²⁵ ⁷³⁰ ⁷³⁵ ⁷⁴⁰ ⁷⁴⁵ ⁷⁵⁰ ⁷⁵⁵ ⁷⁶⁰ ⁷⁶⁵ ⁷⁷⁰ ⁷⁷⁵ ⁷⁸⁰ ⁷⁸⁵ ⁷⁹⁰ ⁷⁹⁵ ⁸⁰⁰ ⁸⁰⁵ ⁸¹⁰ ⁸¹⁵ ⁸²⁰ ⁸²⁵ ⁸³⁰ ⁸³⁵ ⁸⁴⁰ ⁸⁴⁵ ⁸⁵⁰ ⁸⁵⁵ ⁸⁶⁰ ⁸⁶⁵ ⁸⁷⁰ ⁸⁷⁵ ⁸⁸⁰ ⁸⁸⁵ ⁸⁹⁰ ⁸⁹⁵ ⁹⁰⁰ ⁹⁰⁵ ⁹¹⁰ ⁹¹⁵ ⁹²⁰ ⁹²⁵ ⁹³⁰ ⁹³⁵ ⁹⁴⁰ ⁹⁴⁵ ⁹⁵⁰ ⁹⁵⁵ ⁹⁶⁰ ⁹⁶⁵ ⁹⁷⁰ ⁹⁷⁵ ⁹⁸⁰ ⁹⁸⁵ ⁹⁹⁰ ⁹⁹⁵ ¹⁰⁰⁰ ¹⁰⁰⁵ ¹⁰¹⁰ ¹⁰¹⁵ ¹⁰²⁰ ¹⁰²⁵ ¹⁰³⁰ ¹⁰³⁵ ¹⁰⁴⁰ ¹⁰⁴⁵ ¹⁰⁵⁰ ¹⁰⁵⁵ ¹⁰⁶⁰ ¹⁰⁶⁵ ¹⁰⁷⁰ ¹⁰⁷⁵ ¹⁰⁸⁰ ¹⁰⁸⁵ ¹⁰⁹⁰ ¹⁰⁹⁵ ¹¹⁰⁰ ¹¹⁰⁵ ¹¹¹⁰ ¹¹¹⁵ ¹¹²⁰ ¹¹²⁵ ¹¹³⁰ ¹¹³⁵ ¹¹⁴⁰ ¹¹⁴⁵ ¹¹⁵⁰ ¹¹⁵⁵ ¹¹⁶⁰ ¹¹⁶⁵ ¹¹⁷⁰ ¹¹⁷⁵ ¹¹⁸⁰ ¹¹⁸⁵ ¹¹⁹⁰ ¹¹⁹⁵ ¹²⁰⁰ ¹²⁰⁵ ¹²¹⁰ ¹²¹⁵ ¹²²⁰ ¹²²⁵ ¹²³⁰ ¹²³⁵ ¹²⁴⁰ ¹²⁴⁵ ¹²⁵⁰ ¹²⁵⁵ ¹²⁶⁰ ¹²⁶⁵ ¹²⁷⁰ ¹²⁷⁵ ¹²⁸⁰ ¹²⁸⁵ ¹²⁹⁰ ¹²⁹⁵ ¹³⁰⁰ ¹³⁰⁵ ¹³¹⁰ ¹³¹⁵ ¹³²⁰ ¹³²⁵ ¹³³⁰ ¹³³⁵ ¹³⁴⁰ ¹³⁴⁵ ¹³⁵⁰ ¹³⁵⁵ ¹³⁶⁰ ¹³⁶⁵ ¹³⁷⁰ ¹³⁷⁵ ¹³⁸⁰ ¹³⁸⁵ ¹³⁹⁰ ¹³⁹⁵ ¹⁴⁰⁰ ¹⁴⁰⁵ ¹⁴¹⁰ ¹⁴¹⁵ ¹⁴²⁰ ¹⁴²⁵ ¹⁴³⁰ ¹⁴³⁵ ¹⁴⁴⁰ ¹⁴⁴⁵ ¹⁴⁵⁰ ¹⁴⁵⁵ ¹⁴⁶⁰ ¹⁴⁶⁵ ¹⁴⁷⁰ ¹⁴⁷⁵ ¹⁴⁸⁰ ¹⁴⁸⁵ ¹⁴⁹⁰ ¹⁴⁹⁵ ¹⁵⁰⁰ ¹⁵⁰⁵ ¹⁵¹⁰ ¹⁵¹⁵ ¹⁵²⁰ ¹⁵²⁵ ¹⁵³⁰ ¹⁵³⁵ ¹⁵⁴⁰ ¹⁵⁴⁵ ¹⁵⁵⁰ ¹⁵⁵⁵ ¹⁵⁶⁰ ¹⁵⁶⁵ ¹⁵⁷⁰ ¹⁵⁷⁵ ¹⁵⁸⁰ ¹⁵⁸⁵ ¹⁵⁹⁰ ¹⁵⁹⁵ ¹⁶⁰⁰ ¹⁶⁰⁵ ¹⁶¹⁰ ¹⁶¹⁵ ¹⁶²⁰ ¹⁶²⁵ ¹⁶³⁰ ¹⁶³⁵ ¹⁶⁴⁰ ¹⁶⁴⁵ ¹⁶⁵⁰ ¹⁶⁵⁵ ¹⁶⁶⁰ ¹⁶⁶⁵ ¹⁶⁷⁰ ¹⁶⁷⁵ ¹⁶⁸⁰ ¹⁶⁸⁵ ¹⁶⁹⁰ ¹⁶⁹⁵ ¹⁷⁰⁰ ¹⁷⁰⁵ ¹⁷¹⁰ ¹⁷¹⁵ ¹⁷²⁰ ¹⁷²⁵ ¹⁷³⁰ ¹⁷³⁵ ¹⁷⁴⁰ ¹⁷⁴⁵ ¹⁷⁵⁰ ¹⁷⁵⁵ ¹⁷⁶⁰ ¹⁷⁶⁵ ¹⁷⁷⁰ ¹⁷⁷⁵ ¹⁷⁸⁰ ¹⁷⁸⁵ ¹⁷⁹⁰ ¹⁷⁹⁵ ¹⁸⁰⁰ ¹⁸⁰⁵ ¹⁸¹⁰ ¹⁸¹⁵ ¹⁸²⁰ ¹⁸²⁵ ¹⁸³⁰ ¹⁸³⁵ ¹⁸⁴⁰ ¹⁸⁴⁵ ¹⁸⁵⁰ ¹⁸⁵⁵ ¹⁸⁶⁰ ¹⁸⁶⁵ ¹⁸⁷⁰ ¹⁸⁷⁵ ¹⁸⁸⁰ ¹⁸⁸⁵ ¹⁸⁹⁰ ¹⁸⁹⁵ ¹⁹⁰⁰ ¹⁹⁰⁵ ¹⁹¹⁰ ¹⁹¹⁵ ¹⁹²⁰ ¹⁹²⁵ ¹⁹³⁰ ¹⁹³⁵ ¹⁹⁴⁰ ¹⁹⁴⁵ ¹⁹⁵⁰ ¹⁹⁵⁵ ¹⁹⁶⁰ ¹⁹⁶⁵ ¹⁹⁷⁰ ¹⁹⁷⁵ ¹⁹⁸⁰ ¹⁹⁸⁵ ¹⁹⁹⁰ ¹⁹⁹⁵ ²⁰⁰⁰ ²⁰⁰⁵ ²⁰¹⁰ ²⁰¹⁵ ²⁰²⁰ ²⁰²⁵ ²⁰³⁰ ²⁰³⁵ ²⁰⁴⁰ ²⁰⁴⁵ ²⁰⁵⁰ ²⁰⁵⁵ ²⁰⁶⁰ ²⁰⁶⁵ ²⁰⁷⁰ ²⁰⁷⁵ ²⁰⁸⁰ ²⁰⁸⁵ ²⁰⁹⁰ ²⁰⁹⁵ ²¹⁰⁰ ²¹⁰⁵ ²¹¹⁰ ²¹¹⁵ ²¹²⁰ ²¹²⁵ ²¹³⁰ ²¹³⁵ ²¹⁴⁰ ²¹⁴⁵ ²¹⁵⁰ ²¹⁵⁵ ²¹⁶⁰ ²¹⁶⁵ ²¹⁷⁰ ²¹⁷⁵ ²¹⁸⁰ ²¹⁸⁵ ²¹⁹⁰ ²¹⁹⁵ ²²⁰⁰ ²²⁰⁵ ²²¹⁰ ²²¹⁵ ²²²⁰ ²²²⁵ ²²³⁰ ²²³⁵ ²²⁴⁰ ²²⁴⁵ ²²⁵⁰ ²²⁵⁵ ²²⁶⁰ ²²⁶⁵ ²²⁷⁰ ²²⁷⁵ ²²⁸⁰ ²²⁸⁵ ²²⁹⁰ ²²⁹⁵ ²³⁰⁰ ²³⁰⁵ ²³¹⁰ ²³¹⁵ ²³²⁰ ²³²⁵ ²³³⁰ ²³³⁵ ²³⁴⁰ ²³⁴⁵ ²³⁵⁰ ²³⁵⁵ ²³⁶⁰ ²³⁶⁵ ²³⁷⁰ ²³⁷⁵ ²³⁸⁰ ²³⁸⁵ ²³⁹⁰ ²³⁹⁵ ²⁴⁰⁰ ²⁴⁰⁵ ²⁴¹⁰ ²⁴¹⁵ ²⁴²⁰ ²⁴²⁵ ²⁴³⁰ ²⁴³⁵ ²⁴⁴⁰ ²⁴⁴⁵ ²⁴⁵⁰ ²⁴⁵⁵ ²⁴⁶⁰ ²⁴⁶⁵ ²⁴⁷⁰ ²⁴⁷⁵ ²⁴⁸⁰ ²⁴⁸⁵ ²⁴⁹⁰ ²⁴⁹⁵ ²⁵⁰⁰ ²⁵⁰⁵ ²⁵¹⁰ ²⁵¹⁵ ²⁵²⁰ ²⁵²⁵ ²⁵³⁰ ²⁵³⁵ ²⁵⁴⁰ ²⁵⁴⁵ ²⁵⁵⁰ ²⁵⁵⁵ ²⁵⁶⁰ ²⁵⁶⁵ ²⁵⁷⁰ ²⁵⁷⁵ ²⁵⁸⁰ ²⁵⁸⁵ ²⁵⁹⁰ ²⁵⁹⁵ ²⁶⁰⁰ ²⁶⁰⁵ ²⁶¹⁰ ²⁶¹⁵ ²⁶²⁰ ²⁶²⁵ ²⁶³⁰ ²⁶³⁵ ²⁶⁴⁰ ²⁶⁴⁵ ²⁶⁵⁰ ²⁶⁵⁵ ²⁶⁶⁰ ²⁶⁶⁵ ²⁶⁷⁰ ²⁶⁷⁵ ²⁶⁸⁰ ²⁶⁸⁵ ²⁶⁹⁰ ²⁶⁹⁵ ²⁷⁰⁰ ²⁷⁰⁵ ²⁷¹⁰ ²⁷¹⁵ ²⁷²⁰ ²⁷²⁵ ²⁷³⁰ ²⁷³⁵ ²⁷⁴⁰ ²⁷⁴⁵ ²⁷⁵⁰ ²⁷⁵⁵ ²⁷⁶⁰ ²⁷⁶⁵ ²⁷⁷⁰ ²⁷⁷⁵ ²⁷⁸⁰ ²⁷⁸⁵ ²⁷⁹⁰ ²⁷⁹⁵ ²⁸⁰⁰ ²⁸⁰⁵ ²⁸¹⁰ ²⁸¹⁵ ²⁸²⁰ ²⁸²⁵ ²⁸³⁰ ²⁸³⁵ ²⁸⁴⁰ ²⁸⁴⁵ ²⁸⁵⁰ ²⁸⁵⁵ ²⁸⁶⁰ ²⁸⁶⁵ ²⁸⁷⁰ ²⁸⁷⁵ ²⁸⁸⁰ ²⁸⁸⁵ ²⁸⁹⁰ ²⁸⁹⁵ ²⁹⁰⁰ ²⁹⁰⁵ ²⁹¹⁰ ²⁹¹⁵ ²⁹²⁰ ²⁹²⁵ ²⁹³⁰ ²⁹³⁵ ²⁹⁴⁰ ²⁹⁴⁵ ²⁹⁵⁰ ²⁹⁵⁵ ²⁹⁶⁰ ²⁹⁶⁵ ²⁹⁷⁰ ²⁹⁷⁵ ²⁹⁸⁰ ²⁹⁸⁵ ²⁹⁹⁰ ²⁹⁹⁵ ³⁰⁰⁰ ³⁰⁰⁵ ³⁰¹⁰ ³⁰¹⁵ ³⁰²⁰ ³⁰²⁵ ³⁰³⁰ ³⁰³⁵ ³⁰⁴⁰ ³⁰⁴⁵ ³⁰⁵⁰ ³⁰⁵⁵ ³⁰⁶⁰ ³⁰⁶⁵ ³⁰⁷⁰ ³⁰⁷⁵ ³⁰⁸⁰ ³⁰⁸⁵ ³⁰⁹⁰ ³⁰⁹⁵ ³¹⁰⁰ ³¹⁰⁵ ³¹¹⁰ ³¹¹⁵ ³¹²⁰ ³¹²⁵ ³¹³⁰ ³¹³⁵ ³¹⁴⁰ ³¹⁴⁵ ³¹⁵⁰ ³¹⁵⁵ ³¹⁶⁰ ³¹⁶⁵ ³¹⁷⁰ ³¹⁷⁵ ³¹⁸⁰ ³¹⁸⁵ ³¹⁹⁰ ³¹⁹⁵ ³²⁰⁰ ³²⁰⁵ ³²¹⁰ ³²¹⁵ ³²²⁰ ³²²⁵ ³²³⁰ ³²³⁵ ³²⁴⁰ ³²⁴⁵ ³²⁵⁰ ³²⁵⁵ ³²⁶⁰ ³²⁶⁵ ³²⁷⁰ ³²⁷⁵ ³²⁸⁰ ³²⁸⁵ ³²⁹⁰ ³²⁹⁵ ³³⁰⁰ ³³⁰⁵ ³³¹⁰ ³³¹⁵ ³³²⁰ ³³²⁵ ³³³⁰ ³³³⁵ ³³⁴⁰ ³³⁴⁵ ³³⁵⁰ ³³⁵⁵ ³³⁶⁰ ³³⁶⁵ ³³⁷⁰ ³³⁷⁵ ³³⁸⁰ ³³⁸⁵ ³³⁹⁰ ³³⁹⁵ ³⁴⁰⁰ ³⁴⁰⁵ ³⁴¹⁰ ³⁴¹⁵ ³⁴²⁰ ³⁴²⁵ ³⁴³⁰ ³⁴³⁵ ³⁴⁴⁰ ³⁴⁴⁵ ³⁴⁵⁰ ³⁴⁵⁵ ³⁴⁶⁰ ³⁴⁶⁵ ³⁴⁷⁰ ³⁴⁷⁵ ³⁴⁸⁰ ³⁴⁸⁵ ³⁴⁹⁰ ³⁴⁹⁵ ³⁵⁰⁰ ³⁵⁰⁵ ³⁵¹⁰ ³⁵¹⁵ ³⁵²⁰ ³⁵²⁵ ³⁵³⁰ ³⁵³⁵ ³⁵⁴⁰ ³⁵⁴⁵ ³⁵⁵⁰ ³⁵⁵⁵ ³⁵⁶⁰ ³⁵⁶⁵ ³⁵⁷⁰ ³⁵⁷⁵ ³⁵⁸⁰ ³⁵⁸⁵ ³⁵⁹⁰ ³⁵⁹⁵ ³⁶⁰⁰ ³⁶⁰⁵ ³⁶¹⁰ ³⁶¹⁵ ³⁶²⁰ ³⁶²⁵ ³⁶³⁰ ³⁶³⁵ ³⁶⁴⁰ ³⁶⁴⁵ ³⁶⁵⁰ ³⁶⁵⁵ ³⁶⁶⁰ ³⁶⁶⁵ ³⁶⁷⁰ ³⁶⁷⁵ ³⁶⁸⁰ ³⁶⁸⁵ ³⁶⁹⁰ ³⁶⁹⁵ ³⁷⁰⁰ ³⁷⁰⁵ ³⁷¹⁰ ³⁷¹⁵ ³⁷²⁰ ³⁷²⁵ ³⁷³⁰ ³⁷³⁵ ³⁷⁴⁰ ³⁷⁴⁵ ³⁷⁵⁰ ³⁷⁵⁵ ³⁷⁶⁰ ³⁷⁶⁵ ³⁷⁷⁰ ³⁷⁷⁵ ³⁷⁸⁰ ³⁷⁸⁵ ³⁷⁹⁰ ³⁷⁹⁵ ³⁸⁰⁰ ³⁸⁰⁵ ³⁸¹⁰ ³⁸¹⁵ ³⁸²⁰ ³⁸²⁵ ³⁸³⁰ ³⁸³⁵ ³⁸⁴⁰ ³⁸⁴⁵ ³⁸⁵⁰ ³⁸⁵⁵ ³⁸⁶⁰ ³⁸⁶⁵ ³⁸⁷⁰ ³⁸⁷⁵ ³⁸⁸⁰ ³⁸⁸⁵ ³⁸⁹⁰ ³⁸⁹⁵ ³⁹⁰⁰ ³⁹⁰⁵ ³⁹¹⁰ ³⁹¹⁵ ³⁹²⁰ ³⁹²⁵ ³⁹³⁰ ³⁹³⁵ ³⁹⁴⁰ ³⁹⁴⁵ ³⁹⁵⁰ ³⁹⁵⁵ ³⁹⁶⁰ ³⁹⁶⁵ ³⁹⁷⁰ ³⁹⁷⁵ ³⁹⁸⁰ ³⁹⁸⁵ ³⁹⁹⁰ ³⁹⁹⁵ ⁴⁰⁰⁰ ⁴⁰⁰⁵ ⁴⁰¹⁰ ⁴⁰¹⁵ ⁴⁰²⁰ ⁴⁰²⁵ ⁴⁰³⁰ ⁴⁰³⁵ ⁴⁰⁴⁰ ⁴⁰⁴⁵ ⁴⁰⁵⁰ ⁴⁰⁵⁵ ⁴⁰⁶⁰ ⁴⁰⁶⁵ ⁴⁰⁷⁰ ⁴⁰⁷⁵ ⁴⁰⁸⁰ ⁴⁰⁸⁵ ⁴⁰⁹⁰ ⁴⁰⁹⁵ ⁴¹⁰⁰ ⁴¹⁰⁵ ⁴¹¹⁰ ⁴¹¹⁵ ⁴¹²⁰ ⁴¹²⁵ ⁴¹³⁰ ⁴¹³⁵ ⁴¹⁴⁰ ⁴¹⁴⁵ ⁴¹⁵⁰ ⁴¹⁵⁵ ⁴¹⁶⁰ ⁴¹⁶⁵ ⁴¹⁷⁰ ⁴¹⁷⁵ ⁴¹⁸⁰ ⁴¹⁸⁵ ⁴¹⁹⁰ ⁴¹⁹⁵ ⁴²⁰⁰ ⁴²⁰⁵ ⁴²¹⁰ ⁴²¹⁵ ⁴²²⁰ ⁴²²⁵ ⁴²³⁰ ⁴²³⁵ ⁴²⁴⁰ ⁴²⁴⁵ ⁴²⁵⁰ ⁴²⁵⁵ ⁴²⁶⁰ ⁴²⁶⁵ ⁴²⁷⁰ ⁴²⁷⁵ ⁴²⁸⁰ ⁴²⁸⁵ ⁴²⁹⁰ ⁴²⁹⁵ ⁴³⁰⁰ ⁴³⁰⁵ ⁴³¹⁰ ⁴³¹⁵ ⁴³²⁰ ⁴³²⁵ ⁴³³⁰ ⁴³³⁵ ⁴³⁴⁰ ⁴³⁴⁵ ⁴³⁵⁰ ⁴³⁵⁵ ⁴³⁶⁰ ⁴³⁶⁵ ⁴³⁷⁰ ⁴³⁷⁵ ⁴³⁸⁰ ⁴³⁸⁵ ⁴³⁹⁰ ⁴³⁹⁵ ⁴⁴⁰⁰ ⁴⁴⁰⁵ ⁴⁴¹⁰ ⁴⁴¹⁵ ⁴⁴²⁰ ⁴⁴²⁵ ⁴⁴³⁰ ⁴⁴³⁵ ⁴⁴⁴⁰ ⁴⁴⁴⁵ ⁴⁴⁵⁰ ⁴⁴⁵⁵ ⁴⁴⁶⁰ ⁴⁴⁶⁵ ⁴⁴⁷⁰ ⁴⁴⁷⁵ ⁴⁴⁸⁰ ⁴⁴⁸⁵ ⁴⁴⁹⁰ ⁴⁴⁹⁵ ⁴⁵⁰⁰ ⁴⁵⁰⁵ ⁴⁵¹⁰ ⁴⁵¹⁵ ⁴⁵²⁰ ⁴⁵²⁵ ⁴⁵³⁰ ⁴⁵³⁵ ⁴⁵⁴⁰ ⁴⁵⁴⁵ ⁴⁵⁵⁰ ⁴⁵⁵⁵ ⁴⁵⁶⁰ ⁴⁵⁶⁵ ⁴⁵⁷⁰ ⁴⁵⁷⁵ ⁴⁵⁸⁰ ⁴⁵⁸⁵ ⁴⁵⁹⁰ ⁴⁵⁹⁵ ⁴⁶⁰⁰ ⁴⁶⁰⁵ ⁴⁶¹⁰ ⁴⁶¹⁵ ⁴⁶²⁰ ⁴⁶²⁵ ⁴⁶³⁰ ⁴⁶³⁵ ⁴⁶⁴⁰ ⁴⁶⁴⁵ ⁴⁶⁵⁰ ⁴⁶⁵⁵ ⁴⁶⁶⁰ ⁴⁶⁶⁵ ⁴⁶⁷⁰ ⁴⁶⁷⁵ ⁴⁶⁸⁰ ⁴⁶⁸⁵ ⁴⁶⁹⁰ ⁴⁶⁹⁵ ⁴⁷⁰⁰ ⁴⁷⁰⁵ ⁴⁷¹⁰ ⁴⁷¹⁵ ⁴⁷²⁰

tion of the process. In this manner, 30-40% of the introduced carbonaceous substance can be converted per hour. The shaft furnace may also be replaced by a rotary tube furnace, operated in a similar manner.

If the carbon dioxide be removed from the resulting mixtures with hydrogen (free from carbon monoxide) in the known manner, for example by washing with water under pressure, this very simple process furnishes perfectly pure hydrogen, in a direct manner, that is, without any chemical purification being required.

Example 2

An intimate mixture is prepared from finely ground, calcined magnesite and wood charcoal, in the proportions of 1: 4 to 1: 5, and a granular mass is formed by the addition of a binding agent, such as a solution of an alkali carbonate. The contact mass is preferably introduced into externally heated tubes. The gaseous mixture to be purified is passed over the heated contact mass in association with the stoichiometric amount of steam, in the proportion 1 mol. H_2O : 1 mol. CO.

Under these conditions, any desired quantities of gaseous mixtures containing carbon monoxide can be converted into carbon dioxide with one and the same charge of contact material, without any increase or diminution of the initial amount of the latter, provided the amount of steam employed corresponds to the carbon monoxide content.

According to a process heretofore proposed, metallic nickel and cobalt, deposited on pumice or other porous carriers, are employed for eliminating the carbon monoxide from water gas, by oxidizing it to carbon dioxide at a temperature of 350-450° C. Within the scope of this process, it is also proposed, by the subsequent or simultaneous passage of steam, to utilize the carbon, deposited in accordance with the reaction

for the process, in accordance with equation

The value, as an improvement, of the present process which, by the employment of a very cheap and insensitive contact mass, solves the problem of the direct gasification of a carbonaceous material such as charcoal in the presence of steam to form hydrogen, low in, or free from, carbon monoxide, and also enables the complete subsequent elimination of carbon monoxide from mixtures of the same kind containing the latter, becomes particularly apparent by comparison with the said known process which merely aims to free water gas from carbon monoxide by subsequent oxidation with the aid of expensive and sensitive catalysts.

I use the term magnesium oxide in the following claims to include not only preformed magnesium oxide but also magnesium compounds yielding magnesium oxide under the temperature conditions of the present process, and mixtures of magnesium oxide with such substances.

What I claim is:

1. The process of obtaining hydrogen, including reacting a mixture of carbon monoxide and steam in the presence of an intimate mixture of a carbonaceous material and magnesium oxide, the steam being present in amount insufficient to react substantially at the working temperature with the carbonaceous material.

2. The process of obtaining hydrogen, including reacting a mixture of carbon monoxide and steam in the presence of an intimate mixture of a carbonaceous material and magnesium oxide at a temperature of substantially 500° C., the steam being present in amount insufficient to react substantially with the carbonaceous material.

3. The process of obtaining hydrogen, including reacting a mixture of carbon monoxide and steam in the presence of a mixture of charcoal and magnesium carbonate, the steam being present in amount insufficient to react substantially at the working temperature with the carbonaceous material.

4. The process of obtaining hydrogen, including reacting a mixture of water gas and steam in the presence of a mixture of charcoal and magnesium carbonate, the steam being present in amount insufficient to react substantially at the working temperature with the carbonaceous material.

5. The process of obtaining hydrogen, including reacting a mixture of water gas and steam in the presence of a mixture comprising 100 parts of charcoal and 5 to 25 parts of magnesium carbonate, the steam being present in amount insufficient to react substantially at the working temperature with the carbonaceous material.

6. The process of obtaining hydrogen, including reacting a mixture of water gas and steam in the presence of an intimate mixture of a carbonaceous material and magnesium oxide, the steam being present in amount insufficient to react substantially at the working temperature with the carbonaceous material.

7. The process of obtaining hydrogen, including reacting a mixture of water gas and steam in the presence of an intimate mixture of a carbonaceous material and magnesium hydroxide, the steam being present in amount insufficient to react substantially at the working temperature with the carbonaceous material.

8. The process of obtaining hydrogen, including reacting a mixture of water gas and steam in the proportion of 1 mol. H_2O : 1 mol. CO in the presence of a mixture of finely ground calcined magnesite and wood charcoal in the proportion of 1:4 to 1:5.

9. The process of obtaining hydrogen, including reacting a mixture of a carbon monoxide-containing gas and steam in the presence of a mixture of a carbonaceous material and magnesium oxide at a temperature of substantially 500° C., the steam being present in amount insufficient to react substantially with the carbonaceous material whereby to form hydrogen and carbon dioxide according to the equation

and washing the so-formed reaction products with water under pressure to remove the carbon dioxide.

10. A process of producing hydrogen, comprising reacting a mixture of carbon monoxide and steam in the presence of a mixture of magnesium oxide and a carbonaceous material, at a temperature below 750° C., the steam being present in amount insufficient to react substantially with the carbonaceous material.

11. A process of producing hydrogen, comprising reacting a mixture of water gas and steam in the presence of a mixture of magnesium oxide and a carbonaceous material, at a temperature below 750° C., the steam being present in amount in-

- sufficient to react substantially with the carbonaceous material.
12. The process of obtaining hydrogen, including reacting a mixture of carbon monoxide and steam in the presence of an intimate mixture of a carbonaceous material and magnesium oxide containing in addition alkali carbonate, the steam being present in amount insufficient to react substantially at the working temperature with the carbonaceous material.
13. The process of obtaining hydrogen, including reacting a mixture of water gas and steam in the presence of a mixture of a carbonaceous material and magnesium oxide containing in addition alkali carbonate, the steam being present in amount insufficient to react substantially at the working temperature with the carbonaceous material.
14. The process of obtaining hydrogen, including reacting a mixture of water gas and steam in the presence of a mixture of a carbonaceous material and magnesium oxide formed to a granular mass by the addition of an alkali carbonate, the steam being present in amount insufficient to react substantially at the working temperature with the carbonaceous material. 5
15. The process of obtaining hydrogen, including reacting a mixture of water gas and steam in the presence of a mixture of finely ground calcined magnesite and wood charcoal in the proportion of 1:4 to 1:5 made into a granular mass by the addition of an alkali carbonate, the steam being present in amount insufficient to react substantially at the working temperature with the carbonaceous material. 15

FRITZ HANSGIRG.

Certificate of Correction

Reissue No. 19,733.

October 22, 1935.

FRITZ HANSGIRG

It is hereby certified that error appears in the printed specification of the above numbered patent requiring correction as follows: Page 3, first column, line 46, for "C+2H₂=2H₂," read C+2H₂O=2H₂; and that the said Letters Patent should be read with this correction therein that the same may conform to the record of the case in the Patent Office.

Signed and sealed this 17th day of December, A. D. 1935.

[SEAL]

LESLIE FRAZER,
Acting Commissioner of Patents.

- sufficient to react substantially with the carbonaceous material.
12. The process of obtaining hydrogen, including reacting a mixture of carbon monoxide and steam in the presence of an intimate mixture of a carbonaceous material and magnesium oxide containing in addition alkali carbonate, the steam being present in amount insufficient to react substantially at the working temperature with the carbonaceous material.
13. The process of obtaining hydrogen, including reacting a mixture of water gas and steam in the presence of a mixture of a carbonaceous material and magnesium oxide containing in addition alkali carbonate, the steam being present in amount insufficient to react substantially at the working temperature with the carbonaceous material.
14. The process of obtaining hydrogen, including reacting a mixture of water gas and steam in the presence of a mixture of a carbonaceous material and magnesium oxide formed to a granular mass by the addition of an alkali carbonate, the steam being present in amount insufficient to react substantially at the working temperature with the carbonaceous material. 5
15. The process of obtaining hydrogen, including reacting a mixture of water gas and steam in the presence of a mixture of finely ground calcined magnesite and wood charcoal in the proportion of 1:4 to 1:5 made into a granular mass by the addition of an alkali carbonate, the steam being present in amount insufficient to react substantially at the working temperature with the carbonaceous material. 15

FRITZ HANSGIRG.

Certificate of Correction

Reissue No. 19,733.

October 22, 1935.

FRITZ HANSGIRG

It is hereby certified that error appears in the printed specification of the above numbered patent requiring correction as follows: Page 3, first column, line 46, for "C+2H₂=2H₂," read C+2H₂O=2H₂; and that the said Letters Patent should be read with this correction therein that the same may conform to the record of the case in the Patent Office.

Signed and sealed this 17th day of December, A. D. 1935.

[SEAL]

LESLIE FRAZER,
Acting Commissioner of Patents.
